DOOR KNOCKER

Ade Bethune, Newport, R.I., assignor to Terra-Sancta Creations, Inc., Philadelphia, Pa.

Filed Apr. 8, 1970, Ser. No. 22,320

Term of patent 14 years

Int. Cl. D8—03

U.S. Cl. D8—177

Fig. 4.

Fig. 1.

Fig. 2.

Fig. 3.

Fig. 5.

FIG. 1 is a front elevational view of the door knocker of my invention;

FIG. 2 is a side view thereof, the opposite side not being shown but being similar;

FIG. 3 is a back elevational view thereof; and

FIGS. 4 and 5 being top and bottom plan views, respectively, of the door knocker.

While the letters on the front of the door knocker have been shown in specific colors, it will be understood that the colors thereof may vary, or be omitted entirely, without departing from the scope of this invention.

I claim:

The ornamental design for a door knocker, as shown and described.
